UNITED STATES PATENT OFFICE

151,695

DESIGN FOR A STRAW HOLDER

Henry Edgar Kelley, Jr., Kirkwood, Mo., assignor
to Glenmore Distilleries Company, Louisville,
Ky., a corporation of Delaware

Application April 15, 1947, Serial No. 138,414

Term of patent 3½ years

(Cl. 2—3)

To all whom it may concern:

Be it known that I, Henry Edgar Kelley, Jr., a citizen of the United States, residing at Kirkwood, in the county of St. Louis and State of Missouri, have invented a new, original, and ornamental Design for Straw Holder, of which the following is a specification, reference being had to the accompanying drawing, forming part thereof. In the drawing:

I claim:
The ornamental design for a straw holder, as shown.

HENRY EDGAR KELLEY, JR.
